UNITED STATES PATENT OFFICE.

OVERTON WINSTON, OF MINNEAPOLIS, MINNESOTA.

LAMP-SOCKET.

1,259,186.

Specification of Letters Patent. Patented Mar. 12, 1918.

Application filed June 7, 1916. Serial No. 102,213.

To all whom it may concern:

Be it known that I, OVERTON WINSTON, a citizen of the United States, residing at Minneapolis, in the county of Hennepin and 5 State of Minnesota, have invented certain new and useful Improvements in Lamp-Sockets; and I do hereby declare the following to be a full, clear, and exact description of the invention, such as will enable 10 others skilled in the art to which it appertains to make and use the same.

My present invention has for its object to provide an improved adjustable lamp socket especially adapted for use in electric 15 headlights, and is in the nature of an improvement on, or modification of the socket disclosed and broadly claimed in my pending application S. N. 86,851, filed March 27, 1916, and entitled, "Headlights." 20 In the accompanying drawings which illustrate the invention, like characters indicate like parts throughout the several views.

Referring to the drawings:

25 Figure 1 is a view partly in vertical section and partly in elevation with some parts broken away, showing the improved socket and an electric light bulb held thereby; and

Fig. 2 is a view corresponding to Fig. 1, 30 but illustrating a slightly modified construction.

In both views, the numeral 1 indicates an electric light bulb of the single base type having on its shank a surrounding metal 35 sleeve 2 that constitutes one of the contacts of the bulb and having an axial metal disk 3 that constitutes the other contact of the said light bulb. This light bulb is, or may be, of the well known Ediswan type. The 40 contact sleeve 2 has radially projecting lock lugs 4, and is adapted to be telescoped into a holding collar 5 that is provided with an externally threaded eccentric 5^a. The lock lugs 4 are adapted to be inserted into corresponding longitudinal internal grooves 6 45 of the holding collar 5 and to be turned into engagement with a corrugated internal shoulder 7 of said holding collar.

The eccentric externally threaded portion 50 5^a of the holding collar 5 is screwed into the internally threaded portion of a socket sleeve 8, which, at its rear end, has a rigidly secured plug 9 of insulating material. This 55 plug 9 has a forwardly projecting reduced

hub or boss 10, and projecting axially therefrom, is a forwardly spring-pressed contact plunger 11 that engages the axial contact boss 3 of the lamp shank, when the light is in position. The so-called collar 5 and sleeve 8 constitute an adjustable lamp 60 socket in which the sleeve 8 is the relatively fixed member and the collar the relatively adjustable member.

In the construction illustrated in Fig. 1, 65 the holding collar 5, which is, of course, of metal, is provided at its extreme inner end with rigidly secured supplemental section in the form of a ring 12. This ring 12 affords a base of re-action for the front end of a coiled spring 13, the rear end of which 70 surrounds the boss 10 and bears against the body portion of an insulating plug 9. The said boss and the ring 12 hold the spring 13 concentric with, but spaced from the interior threaded portion of the sleeve 8. 75 The said spring puts the threaded engagement between the eccentric and sleeve under tension, so that the eccentric is not liable to be accidentally rotated.

In the construction illustrated in Fig. 2, 80 a tapered coiled spring 14 which performs the same function as the spring 13 in the other construction, is seated at its contracted rear end around the boss 10 and against the plug 9, and at its front end, is seated 85 directly in an annular groove 15 formed in the inner end of the threaded eccentric 5^a. In both arrangements, the tension springs for preventing accidental rotation of the eccentric and holding collar, are properly 90 held out of engagement with the internal threads of the sleeve 8 so that it is immaterial whether the said threads and the spring have or have not spiral travel in the same direction, since interlocking engagement between the two cannot take place. In a lamp socket of this character, one of the leads of the circuit for supplying the lamp 95 will be connected to the contact plunger 11 and the other will be connected to the 100 sleeve 8.

What I claim is:

In a lamp socket, the combination with an internally threaded socket sleeve and a lamp holding collar having an eccentric portion 105 provided with external threads engaging the threads of said socket sleeve, an insulating plug in the rear end of said socket sleeve

having a forwardly projecting boss, and a coiled tension spring seated at its rear end against said plug and around said boss and seated at its front end in the eccentric portion of said holding sleeve and thereby held out of contact with the threaded inner walls of said socket sleeve.

In testimony wherof I affix my signature, in presence of two witnesses.

OVERTON WINSTON,

Witnesses:

CLARA DEMAREST,
BERNICE G. WHEELER.
